United States Patent Office

Des. 228,356
Patented Sept. 11, 1973

228,356

ROLLER SKATE

Beverly W. Taylor, Hermann, Mo., assignor to Steven
Manufacturing Co., Hermann, Mo.

Filed Sept. 27, 1971, Ser. No. 184,333

Term of patent 7 years

Int. Cl. D21—02

U.S. Cl. D34—15 M

FIG. 1.

FIG. 2.

FIG. 3.

FIG. 4.

FIG. 5.

FIG. 6.

FIG. 1 is a rear perspective view of a roller skate showing my new design;

FIG. 2 is a front elevational view thereof;

FIG. 3 is a side elevational view thereof, the opposite side being a mirror image thereto;

FIG. 4 is a rear elevational view thereof;

FIG. 5 is a top plan view thereof; and

FIG. 6 is a bottom plan view thereof.

I claim:

The ornamental design for a roller skate, as shown and described.
